TAPE EMBOSsing TOOL

Benedict E. Bogaeus, 10350 Sunset Blvd.,
Los Angeles, Calif.

Filed Dec. 26, 1963, Ser. No. 77,934

Term of patent 14 years

(Cl. D64—10)

FIG. 1 is a side perspective view of a tape embossing tool showing my new design;

FIG. 2 is an elevational view of the side opposite to that of FIG. 1;

FIG. 3 is a top plan view;

FIG. 4 is a bottom plan view;

FIG. 5 is a front elevational view thereof; and

FIG. 6 is a rear elevational view thereof.

I claim:

The ornamental design for a tape embossing tool, substantially as shown.
